VACUUM TUBE MODE LOCK FORMING APPARATUS

Emil Sirp, Downers Grove, Ill., assignor to Western Electric Company, Incorporated, New York, N. Y., a corporation of New York

Application June 17, 1943, Serial No. 491,130

10 Claims. (Cl. 140—71)

This invention relates to article forming apparatus and more particularly to a punch press operated apparatus for forming vacuum tube mode locks.

In the manufacture of mode locks for controlling characteristics of vacuum tubes, it is necessary that the mode locks be formed to a predetermined configuration with a high degree of accuracy so that they will effectively serve their purpose in the vacuum tube into which they are to be assembled.

It is an object of the present invention to provide a simple apparatus for rapidly and accurately forming articles.

In accordance with one embodiment of the invention, apparatus is provided for forming a mode lock, which comprises an arcuately shaped body portion with integrally formed tips extending at right angles to the arcuate portion thereof. A series of horizontally and vertically movable tools adapted for actuation by a punch press ram serve to successively shear a section of cylindrical stock from a supply thereof, grip the sheared off portion, and bend it to arcuate configuration by sliding horizontally and thereafter the same tools are moved vertically to carry the arcuately shaped part against fixed abutments which serve to bend the ends of the formed part at right angles to the arcuate portion thereof. The stock to be formed is automatically fed to the shearing and forming tool by any suitable feeding device adapted to be actuated by the punch press ram in its reciprocation.

A better understanding of the invention will be had by reference to the following detailed description when considered in conjunction with the accompanying drawings; wherein

Fig. 1 is a plan section showing the bed of a punch press in elevation and the tools mounted thereon and showing the liner pins of the press and some of the actuating members for the tools in section;

Fig. 2 is a transverse vertical sectional view taken substantially along the line 2—2 of Fig. 1 in the direction of the arrows;

Fig. 3 is a vertical sectional view taken along the line 3—3 of Fig. 1 in the direction of the arrows;

Fig. 4 is an enlarged fragmentary detailed plan view showing the tools in the position they occupy after a section of stock has been cut off and bent to arcuate configuration and prior to the forming of the upstanding tips thereon;

Fig. 5 is a vertical sectional view taken substantially along the line 5—5 of Fig. 4 in the

direction of the arrows, parts being broken away to illustrate more clearly the construction of the tools and their relative position in the apparatus;

Fig. 6 is a fragmentary detail view in plan showing the cut-off part after the ends thereof have been bent upwardly;

Fig. 7 is a fragmentary sectional view taken substantially along the line 7—7 of Fig. 6 in the direction of the arrows; and

Fig. 8 is a detail view of the mode lock formed in the apparatus showing the various positions of the stock in dot and dash lines.

In the drawings, wherein like reference characters designate the same parts throughout the several views, there is shown in Fig. 8 a mode lock, designated generally by the numeral 10, which is to be formed in the apparatus constituting the present invention. The mode lock 10 has an arcuately shaped section 11 and upwardly extending tips 12 and 13. In the operation of the apparatus, stock, as indicated by the dot and dash lines 14, is fed into the press and in the first portion of the down-stroke of the ram of the press, as will be described more in detail hereinafter, the stock is cut off at 15 and bent to form the arcuately shaped section 11 which has the straight extensions 16 and 17 at its ends, which are, in a subsequent operation of the apparatus, bent upwardly to form the tips 12 and 13. The stock 14 is fed from a suitable supply thereof (not shown) by any suitable feeding mechanism, which includes a cam roller 20 mounted on an actuator rod 21 of the stock feeding device and held in position to be moved to the right (Fig. 3) by a cam 22 mounted upon a ram 23 of a punch press. As is usual in apparatus of this type, the cam 22 will, on the down-stroke of the ram 23, force the actuator rod 21 to the right through the interaction of the cam roller 20 to prepare the stock feeding device for feeding a predetermined length of stock 14 into the apparatus on the up-stroke of the ram 23. The cam roller 20, as pointed out hereinbefore, is mounted on the end of the actuator rod 21 and the actuator rod 21 is slidable to the right and left (Fig. 3) to effect feeding of the stock, being suitably mounted on a base 24 of the stock feeding mechanism, which is, in turn, suitably secured to a bolster plate 25 mounted upon a bed 26 of a punch press which includes the ram 23.

The mechanism for actuating the ram 23 of the punch has not been shown in detail hereinbefore, but may comprise any suitable punch press mechanism adapted for automatic operation to repeatedly force the ram 23 downwardly from

the position shown in Figs. 2 and 3, and then retract it to that position. The ram of the punch press 23 has the usual guide sleeves 27-27 mounted in it for receiving liner pins 28-28 mounted on the bolster plate 25 to insure the proper registration of the various mechanisms carried by the ram with those mounted on the bed 26 and bolster plate 25 of the press.

A bracket 29 (Fig. 1) attached to the bolster plate 25 by means of socket head screws 30 is provided with a shearing face 31 and a guide aperture 32. The stock 14 is directed, by the stock feeding mechanism, through the guide aperture 32 each time the ram 23 is moved upwardly and a length of stock will be cut off from the supply thereof by a shearing edge 33 (Fig. 4) formed on a tool 34 cooperating with the shearing face 31 of the bracket 29. The tool 34 is mounted upon a tool supporting slide 35, as seen most clearly in Figs. 2, 5 and 7, which is slidably mounted on a slide supporting plate 36. The tool supporting slide 35 is held on the plate by cooperating rails 37 and 38, which, together with the plate 36, form ways for guiding the tool supporting slide in its travel.

The slide supporting plate 36 is mounted upon a pair of posts 50 and 51, which are slidable in apertures 52 and 53 formed in the bolster plate 25 and the plate 36 is urged upwardly to the position shown in Figs. 2 and 5 by compression springs 54-54, 55-55 and 56-56. The springs 54, 55 and 56 surround headed retainer pins 45-45 and are seated in recesses 46-46 and 47-47 formed in the under surface of the plate 36 and the upper surface of the bolster plate 25, respectively. The shanks of the retainer pins 45-45 are threaded into the plate 36 and are freely slidable in shouldered apertures 48-48 formed in the bolster plate 25 coaxially with the recesses 47-47 in such manner that the heads on the retainer pins will engage shoulders 49-49 and limit the upward movement of the plate 36 with respect to the bolster plate 25.

Formed in the tool supporting slide 35 is a recess 57 (Fig. 2) in which a V-shaped leaf spring 58 is secured by means of a machine screw 59. The two legs of the leaf spring, as shown most clearly in Fig. 1, normally support a pair of pins 60-60 in the position shown in Figs. 2 and 5. The pins 60, being thus carried by the tool supporting slide 35, are normally held in the position shown in Fig. 2, but when the tool supporting slide 35 is shifted to the position shown in Fig. 5, as will be described hereinafter, the pins 60 are moved over into vertical registration with stationary pins 61-61, extending upwardly from the bolster plate 25. The tool supporting slide 35 has a cam slot formed in it, which is defined by the cam faces 62 and 63. A continuation of the cam face 62 is formed on a plate 64, which is suitably attached on the upper surface of the tool supporting slide 35.

Slidable in shouldered apertures 65-65 in the plate 64 are a pair of stripper actuating rods 66, which have their right ends (Figs. 1 and 2) threaded into a stripper supporting plate 67, which, in turn, carries a stripper finger 68. Surrounding the stripper actuating rods 66 are compression springs 69-69, which bear against shoulders formed in the apertures 65 and urge the stripper supporting plate 67 to the right (Figs. 1 and 2). Mounted on the underside of the ram 23 is a cam member 75 having cam faces 76 and 77 adapted to engage the cam faces 62 and 63 on the tool supporting slide 35 to shift

the tool supporting slide to the right and left, respectively (Fig. 2), when the ram 23 is moved downwardly and then upwardly.

Positioned to cooperate with the tool 34 is a tool 78 having an arcuately shaped and shouldered forming edge 79. The tool 78 is mounted upon a tool supporting slide 80, which is slidable between rails 81 and 82 (Fig. 1) mounted upon a slide supporting plate 83. The slide supporting plate 83 is similar to the plate 36, and is normally urged to the position shown in Fig. 2 by compression springs 84-84 positioned between it and the upper surface of the bolster plate 25, guide posts 85-85 being fixed to the plate 83 and being slidable in apertures 86-86 formed in the bolster plate 25. The tool supporting slide 80 has a cam slot formed in it which is provided with camming faces 87 and 88 adapted to cooperate with cam faces 89 and 90 on cam member 91, similar to the cam member 75 attached to the ram 23. The cam face 90 is adapted to engage the cam face 88 and cam the tool supporting slide 80 to the left (Fig. 2) when the ram 23 is moved downwardly to carry the tool 78 into engagement with the stock 14 to cooperate with the tool 34 in forming the stock after the shearing edge 33 of the tool 34 has cut a length of stock from the supply.

After the cam members 75 and 91 have cammed the tool supporting slides 35 and 80 toward the stock, to grip, shear and form the stock, continued downward movement of the ram 23 will move an actuator block 95 into engagement with the upper surfaces of the tools 34 and 78 and will push the tools, the tool supporting slides 35 and 80 and the slide supporting plates 36 and 83 downwardly against the action of the compression springs 54, 55, 56 and 84. Since the tools 78 and 34 will, at this time be gripping the sheared off length of stock 14 between them and will have completed the forming of the section 11 of the mode lock 10, the pins 60, which are at this time in alignment with the stationary pins 61, will be held stationary by the pins 61 while the cut-off length of stock and the tools move downwardly, thereby to bend up the tip portions 12 and 13 of the mode lock. The actuator block 95 is provided with recesses 100 and 101 to receive the upwardly bent tips 12 and 13 of the mode lock, which are bent upwardly by the forming pins 60.

A more complete understanding of the apparatus may be had by reference to the following brief description of the mode of operation thereof.

After a supply of stock 14 has been suitably attached to the feeding mechanism and inserted in the guide aperture 32, the punch press may be operated to reciprocate the ram 23. Each time the ram 23 moves downwardly, the cam 22 will strike the cam roller 20 to force the actuator rod 21 to the right and store energy in the feeding mechanism to feed a measured length of stock 14 to the forming and shearing portion of the apparatus. On the first stroke of the ram 23, the product formed may be incomplete, but on each succeeding stroke a complete mode lock 10 will be formed in the apparatus. The length of stock necessary to form a complete mode lock will be fed through the guide aperture 32 on each stroke of the punch press, the feeding of the stock occurring as the punch press ram 23 moves upwardly.

As the ram 23 moves downwardly, the cam members 75 and 91 will move the tool supporting slides 35 and 80 toward each other. The first por-

tion of the tools to engage the stock 14 will be the stripper finger 68, which will clamp the stock between itself and the arcuately shaped and shouldered forming edge 79 of the tool 78. Just after the stock is engaged by the finger 68 and forming edge 79, the shearing edge 33 of the tool 34 will shear the extending length of stock from the supply thereof. As the cam members 75 and 91 continue their downward movement, the sheared-off length of stock will be pinched between the tools 34 and 78 to form the arcuately shaped section 11 (Fig. 8) of the mode lock 10. While the tools are still urged into engagement with the thus partially formed mode lock due to the engagement of the straight portions of the cam members 75 and 91 with the vertical portions of the camming faces 62 and 88, the actuator block 95 will engage the upper surfaces of the tools 34 and 78 and will force the tools and tool supporting slides 35 and 80, together with the slide supporting plates 36 and 83, downwardly. Since the forming pins 60 have been carried over into alignment with the stationary pins 61 due to the movement of the tool slide 35 to the position shown in Fig. 5, the pins 60 will be held stationary while the partially formed mode lock 10 is moved downwardly. The straight extensions 16 and 17 at the ends of the curved or arcuately shaped section 11 will be engaged by the pins 60 due to the movement of the tools 34 and 78 downwardly and the tips 12 and 13 will thus be bent upwardly against the side edges of the tool 78 and in the notch formed by the arcuately shaped surface of the tool 34 and the straight front and rear edges of the tool 78. As the ram 23 moves upwardly, the cam surfaces 77 and 89 on the cam members 75 and 91 will move the tool supporting slides 35 and 80 apart to release the tools 34 and 78 from the formed mode lock 10. However, the mode lock will be held, for a short time, against the tool 78 by the stripper finger 68 as the tool 78 moves to the right (Figs. 1, 2, 4 and 6) and will be carried into alignment with a part receiving aperture or passage 102, into which it will be dropped when finger 68 disengages from it. In this manner, for each reciprocation of the ram 23, a complete mode lock 10 will be formed with a high degree of precision.

What is claimed is:

1. In an article forming apparatus, means for feeding a predetermined length of stock to a predetermined position, tools slideable to engage the stock at said position, means on one of said tools for shearing a length of stock from the supply, means for moving said tools at right angles to their sliding movement, and pins carried by one of said tools for engagement with portions of the length of stock which has been sheared from the supply to bend the ends of the length of stock when the tools move the body of the stock at right angles to the sliding movement of the tools.

2. In an article forming apparatus, a pair of forming tools, means on one of said tools for shearing a length of stock from a supply thereof, a tool supporting slide, a slide supporting plate for resiliently supporting said slide, and a common actuating means for imparting sliding movement to said tools and for moving said tools at right angles to their direction of sliding movement.

3. In an article forming apparatus, a reciprocable ram, a stationary bolster plate associated with the ram, cam members carried by the ram,

tools supported by the bolster plate for actuation by the cam members, tool slides resiliently mounted on the bolster plate for slidably supporting the tools, and means on the ram for moving the tools toward the bolster plate after the tools have been actuated by the cam members.

4. In an article forming apparatus, a reciprocable ram, a stationary bolster plate associated with the ram, cam members carried by the ram, tools supported by the bolster plate for actuation by the cam members, tool slides resiliently mounted on the bolster plate for slidably supporting the tools, means on the ram for moving the tools toward the bolster plate after the tools have been actuated by the cam members, and means on the bolster plate for imparting relative movement to one of the tools with respect to others of the tools when the tool slide is moved toward the bolster plate.

5. In an article forming apparatus, a reciprocable ram, a stationary bolster plate associated with the ram, cam members carried by the ram, tools supported by the bolster plate for actuation by the cam members, tool slides resiliently mounted on the bolster plate for slidably supporting the tools, means on the ram for moving the tools toward the bolster plate after the tools have been actuated by the cam members, a shearing edge on one of said tools for shearing a length of stock from the supply thereof, and a stripper finger carried by one of the tools for clamping the sheared-off part against another tool prior to the completion of the forming of the sheared-off part.

6. In an article forming apparatus, a pair of forming tools, means on one of said tools for shearing a length of stock from a supply thereof, a tool supporting slide, a slide supporting plate for resiliently supporting said slide, a common actuating means for imparting sliding movement to said tools and for moving said tools at right angles to their direction of sliding movement, one of said pair of forming tools being concave and the other being convex to form an arcuate portion in the sheared-off length of stock, and means carried by one of said tools and movable relative thereto for bending the tips of the sheared-off length of stock at right angles to the arcuately formed portion thereof.

7. In an article forming apparatus, a pair of forming tools, means on one of said tools for shearing a length of stock from a supply thereof, a tool supporting slide, a slide supporting plate for resiliently supporting said slide, a common actuating means for imparting sliding movement to said tools and for moving said tools at right angles to their direction of sliding movement, one of said pairs of forming tools being concave and the other being convex to form an arcuate portion in the sheared-off length of stock, means carried by one of said tools and movable relative thereto for bending the tips of the sheared-off length of stock at right angles to the arcuately formed portion thereof, including means on the common actuating means for moving both of the pairs of tools together, forming pins carried by one of said tools and normally held in a predetermined position, and fixed abutments for holding said forming pins stationary while the tools move together.

8. In an apparatus for forming vacuum tube mode locks, a pair of cooperating bending tools movable toward each other to form an arcuate bend in a length of stock, means carried by one

of said forming tools for shearing the length of stock from a supply thereof, forming pins carried by said tool, stationary abutments positioned to align with said forming pins when the bending tools have completed the bending of the arcuate bend, and means for moving said tools to engage the forming pins with the stationary abutments to bend up the ends of the previously bent length of stock.

9. In an apparatus for forming vacuum tube mode locks, a pair of cooperating bending tools movable toward each other to form an arcuate bend in a length of stock, means carried by one of said forming tools for shearing the length of stock from a supply thereof, forming pins carried by said tool, stationary abutments positioned to align with said forming pins when the bending tools have completed the bending of the arcuate bend, means for moving said tools to engage the forming pins with the stationary abutments to bend up the ends of the previously bent length of stock, and means for normally

holding said forming pins in a predetermined position relative to the bending tools.

10. In an apparatus for forming vacuum tube mode locks, a pair of cooperating bending tools movable toward each other to form an arcuate bend in a length of stock, means carried by one of said forming tools for shearing the length of stock from a supply thereof, forming pins carried by said tool, stationary abutments positioned to align with said forming pins when the bending tools have completed the bending of the arcuate bend, means for moving said tools to engage the forming pins with the stationary abutments to bend up the ends of the previously bent and sheared-off length of stock, and means for normally holding said forming pins in a predetermined position relative to the bending tools, said bending tools having cooperating surfaces for engaging the part during the operations thereon by the forming pins.

EMIL SIRP.
